UNITED STATES PATENT OFFICE.

MIAL B. GOODWIN, OF NORPHLET, ARKANSAS.

METALLIC RAILROAD-TIE.

1,159,210.

Specification of Letters Patent.

Patented Nov. 2, 1915.

Application filed July 17, 1915. Serial No. 40,477.

To all whom it may concern:

Be it known that I, MIAL B. GOODWIN, a citizen of the United States, residing at Norphlet, in the county of Union and State 5 of Arkansas, have invented certain new and useful Improvements in Metallic Railroad-Ties; and I do hereby declare the following to be a full, clear, and exact description of the invention, such as will enable others 10 skilled in the art to which it appertains to make and use the same.

This invention relates to new and useful improvements in metallic railroad ties and the principal object of the invention is to 15 provide a simple and efficient tie capable of holding rails against spreading or sinking.

Another object of the invention is to provide a tie having a novel fastening means which will allow the rails to be released 20 upon the proper manipulation, thereby allowing the parts to be replaced.

A further object of the invention is to provide a novel locking means for the rails, which will effectively prevent the rails from 25 becoming accidentally released.

With these and other objects in view, the invention consists in the novel combination and arrangement of parts which will be 30 fully set forth in the following specification and accompanying drawings, in which:—

Figure 1 is a top plan view of a tie constructed in accordance with this invention. Fig. 2 is a sectional view on line 2—2 of Fig. 1. Fig. 3 is a transverse sectional view on 35 line 3—3 of Fig. 2, and Fig. 4 is a detail view of the key used for releasing the device.

Referring now to the drawings by characters of reference, the numeral 1 designates the body of my improved tie, provided with 40 a slot 2, near each end. This body comprises a flat strip of metal, which is preferably rectangular in plan and formed at suitable points in the body are the bolt receiving apertures 3, the use of which will appear as 45 the description proceeds.

Used in connection with the tie hereinbefore referred to is the plate designated generally by the numeral 4 comprising the bodies 5, which are connected by the reduced 50 strip 6. This reduced strip is bent so that its upper face lies flush with the lower face of the enlargement 5 as illustrated in Fig. 2 and the plates 5 are provided with the openings 7, for the reception of the bolts, 55 which secure the device to the body 1. Suitable apertures 8 are formed in the reduced

portion 6 of the plate 4 and are designed to receive the spikes, which will be more fully hereinafter described. Suitable openings 9 are formed in the bodies 5 and these openings are designed to receive the keys, by which the device is unlocked.

Secured to the under side of the tie is the plate designated generally by the numeral 10 comprising a body 11 having formed 60 therein, at suitable intervals, the openings 12 for the reception of the bolts, which secure the plate 4 to the tie and the openings 13 are formed in the plate 9, through which the lower ends of the securing plates extend.

Secured to the under side of the plate 5 and extending downwardly therefrom are the spaced ears 14, the use of which will appear as the description proceeds. Pivoted between the ears are the locking pawls 15 75 having connected thereto, the springs 16 and these pawls are provided with the points 17, which are arranged to engage in notches 18 formed in the attaching spikes 19, the heads 20 of which engage the rail flanges as 80 clearly shown in Fig. 2.

In order to provide a releasing means by which the pawls 15 may be made to disengage the walls of the notches 18 there is provided the key best illustrated in Fig. 4 85 comprising the shank 21, having formed at one end the loop 22. On the opposite end of the shank is the bit 23 and this bit is used to release the pawls, when the key is properly manipulated, thereby permitting the 90 spikes 19 to be withdrawn and allowing the rails to be removed.

It will be apparent from the foregoing that in use the ties are laid in the usual way but the plates 4 and 9 are first put in position as shown in Fig. 2. It will thus be seen that the whole will be assembled and the rails may then be put in place in the depressed portions of the plate 4, so that the under faces of the rails lie flush with the 100 upper face of the tie and with the plate. The spikes 19 are then slipped through the openings 8, in such a way that the heads 20 will engage the flanges when the spikes are driven home and upon forcing the spikes downwardly, it will be seen that they will engage the pawls 15 and upon still further downward movement of the spikes, it will be seen that the lower end will enter the openings 13 in the plates 9. After the spikes 110 have been forced home, it will be seen that the pawls will engage in the notches 18 in

the shanks of the spikes and thereby lock the same against movement. In order to release the tie to replace any worn or broken part, the key 21 is provided which 5 will upon insertion through the opening 9 permit the pawls 15 to be released and thus allow the rails and ties to be removed so that any parts may be renewed or repaired.

While in the foregoing there has been 10 shown and described the preferred embodiment of this invention, it is to be understood that such changes may be made in the combination and arrangement of parts as will fall within the spirit and scope of the 15 appended claims.

What is claimed is:—

1. A tie of the character described comprising a body having openings near each end, plates covering the openings, pawls 20 pivoted to the plates, the plates being pro-

vided with openings, notched spikes extending into the openings, the walls of the notches in the spike being engaged by the pawls and heads on the spikes engaging the rails to hold the same in place.

2. A tie comprising a body provided with slots near each end, plates covering the slots, said plates being provided with alining openings, spikes having notches in their shanks extending through the alining openings, pawls pivoted to the uppermost plate and engaging the walls of the notches in the spikes and means to release the spikes to permit the rails to be removed.

In testimony whereof I affix my signature in presence of two witnesses.

MIAL B. GOODWIN.
